UNITED STATES PATENT OFFICE.

WILLARD C. FISK AND HARRY L. WHITE, OF OROFINO, IDAHO.

TELEPHONE ATTACHMENT.

972,839.

Specification of Letters Patent. Patented Oct. 18, 1910.

Application filed April 14, 1910. Serial No. 555,346.

To all whom it may concern:

Be it known that we, WILLARD C. FISK and HARRY L. WHITE, citizens of the United States, residing at Orofino, in the county of Nez Perce, State of Idaho, have invented certain new and useful Improvements in Telephone Attachments; and we do hereby declare the following to be a full, clear, and exact description of the invention, such as will enable others skilled in the art to which it appertains to make and use the same.

This invention relates to telephone attachments of that general class designed for detecting unauthorized auditors on party lines.

The principal object of this invention is to provide a device of this character that will automatically telegraph the call of a telephone being used to intercept conversation, to the parties engaged in the conversation.

A further object is to provide an audible signal that the intruder will be powerless to suppress after having removed his receiver from the hook.

With the above and other objects in view, the invention consists in general, of a simple device in the nature of an interrupter connected in parallel with the primary circuit and arranged to produce a series of clicks that correspond to the call of the telephone.

In the accompanying drawing, forming part of this specification, Figure 1 is a front elevation of a telephone equipped with an attachment constructed in accordance with our invention, with parts of the casing removed to expose the interior. Fig. 2 is a section on the line 2-2, Fig. 1. Fig. 3 is a section on the line 3-3, Fig. 1. Fig. 4 is a detail perspective view of the interrupter disk.

The reference numeral 8 designates a telephone of the wall or box type having a receiver 9 and a transmitter 10 of the usual and well-known kind.

The telephone attachment comprising the subject matter of this invention consists of a casing 11 adapted to be rigidly secured to the top wall of the telephone 8. Mounted upon the receiver hook 12 is an extensible rod designated in general by the numeral 13, this rod being provided at one end with a clamp 14 which encircles the receiver hook and is secured thereto by a set screw 15. The free end of the rod extends upwardly through

registering openings in the opposed walls of the casing and telephone into the casing 11, and is curved outwardly at its free extremity 16. This curved terminal 16 bears against a transversely disposed stop 17 mounted within the casing and operates to move the rod laterally when the receiver hook 12 is raised. A leaf spring 18 bears against the rear side of the rod 13 and operates to return the rod to its initial position as soon as the receiver hook is depressed by the receiver. Formed on the rod a short distance below its curved extremity is a ledge or shoulder 19 the purpose of which will presently appear.

Rising from the bottom of the casing 11 is a standard 20 having at its upper end a suitable bearing to receive a stub shaft 21. Loosely mounted on the stub shaft is a ratchet disk 22 to the outer side face of which is rigidly secured one end of a link 23 which latter is sufficient in length to engage at its free end the shoulder 19 of the rod 13 when the latter is at rest in its lowest limit of movement. Keyed or otherwise rigidly secured to the stub shaft 21 is a gear 24 which is considerably greater in diameter than the ratchet and is provided on its inner side face with a spring pressed pawl 25 which engages the ratchet. It is now evident that when the receiver is taken from the receiver hook the latter will raise and move upward the rod 13 which latter is cammed outwardly by the stop 17 thereby permitting the link 23 to become disengaged from the shoulder 19. A helical spring 26 secured to the bottom of the casing engages the free end of the link 23 and operates to pull downward the link after the latter has become disengaged from the shoulder, this downward movement of the link serving to rotate the ratchet backwardly, and since the gear 24 is locked by means of the pawl 25 to the ratchet, this gear will rotate simultaneously with the ratchet and in the same direction as the latter. As before stated, the ratchet is loosely mounted on the stub shaft 21 so that when the ratchet is rotated forwardly through the instrumentality of the link 23 when the rod 13 rises, the pawl 25 will slide freely over the periphery of the ratchet and not lock the gear and pawl together so that the gear is at rest during the rising movement of the rod.

Rising from the bottom of the casing 11 is a pair of spaced standards 27 having suitable bearings at their upper ends to receive

a shaft 28. Keyed to the shaft 28 is a pinion 29 which is in mesh with the gear 24. Keyed to the shaft 28 is a semicircular cam disk 30, this disk being preferably less in diameter than the pinion 29 and arranged concentric therewith. Pivoted at one end to the side wall of the casing above the shaft 28 is an L shaped arm 31 one leg of which is held in abutting contact with the cam surface of the disk 30 by a helical spring 32 which engages the leg between its pivot and point of contact with the cam disk as shown, and the other leg of which extends approximately parallel with the bottom of the casing and is supported upon the latter by a guide plate 33. The free end of the L shaped arm is advanced into a notch 34 formed in the rod 18 when the curved surface of the cam bears against the secured leg of this L shaped arm and is retracted from the notch by the helical spring 32 when the flat face of the cam bears against the secured leg. It is now clear that when the L shaped arm is engaged in the notch 34 the receiver hook cannot be depressed manually, but will be locked in its raised position until the flat face of the cam advances into engagement with the L shaped arm as above described. This construction positively prevents the receiver hook being pulled down and a primary circuit broken until a certain time has elapsed after the receiver is taken from the receiver hook, and during this space of time the telegraph mechanism which proclaims an auditor to the persons engaged in conversation will have operated.

The telegraph mechanism consists of a disk 35 formed of wood, fiber or other suitable insulating material and is provided centrally with a metal sleeve 36 which is rigidly secured to the shaft 28 and is insulated therefrom as shown at 37. Secured to the periphery of the disk 35 is a plurality of spaced plates 38, each disk being independently connected to the sleeve 36 by a wire 29 which is preferably countersunk in the side face of the disk. Transversely disposed on each disk is a series of teeth 40, these teeth of sufficient size to project considerably beyond the periphery of each plate as may clearly be seen by referring to Fig. 4. Mounted within the casing are a pair of brush holders 41 of any preferred form and projecting horizontally from these holders are a pair of brushes 42 one of which engages teeth 40 on the periphery of the disk, and the other of which engages the sleeve 36. Wires 43 connect the brushes in parallel with the primary circuit of the telephone as shown in Fig. 1.

Supposing now the telephone call to be one long dash, a short dash, and then another long dash, thus — — —. On the periphery of the disk 27 a long plate 44, a short plate 45 and another long plate 46

will be spaced apart in the order named. When the disk rotates the plates will be carried under the brush that engages the periphery of the disk and the circuit made each time the brush engages a tooth and broken each time the brush passes over the valley between adjacent teeth. It is clear that while the brush is passing over the long plate a long series of makes and breaks in the circuit will occur, and while the brush passes over the short plate a short series of makes and breaks will occur, the two series being separated by a long break in the circuit as the brush passes over the space on the periphery of the disk between the two plates. The long series of breaks and makes will be repeated when the brush reaches the remaining long plate. It is well-known that in telephone construction every make and break in the circuit caused by a third party breaking in on the line will be made audible to the persons engaged in conversation by a sharp click. This is just what occurs when the toothed plates rotate under the brushes, namely, a long series of clicks, a short series of clicks, then another long series of clicks will be heard by both parties engaged in conversation when the telephone designated by the above-described call breaks in on the line.

For securing evenness in the movement of the disk 35 a balance wheel 47 is mounted for rotation in the casing above the disk and is provided on its shaft with a pinion 48 that meshes with a gear 49 which is rigidly secured to the shaft 28. A pawl 50 is secured to the bottom of the casing and engages the gear 49 thereby preventing the mechanism from rotating backward.

The guide plate 33 which supports the L shaped locking arm on the bottom of the casing is provided with an upwardly inclined extension 51 which limits the downward movement of the link 23 so that the latter is maintained in position to again engage the rod 19 when the latter returns to its lowest position of movement so that the telegraphing mechanism is automatic in operation and requires no attention from the operator.

From the foregoing description taken in connection with the accompanying drawing, it is thought that the construction and operation of our invention will be easily understood without a more extended explanation, it being understood that various changes in the minor details of construction may be made within the scope of the appended claim:

What is claimed is:

1. An attachment for telephones consisting of an interrupting device connected with the telephone circuit, means connecting the device to the telephone receiver hook, and means to prevent the telephone circuit from

being opened until the interrupting device has operated.

2. An attachment for telephones, consisting of an interrupting device connected with the telephone circuit, means for operatively connecting the device to the telephone receiver hook, and locking means between the receiver hook and device operating to prevent the telephone circuit from being opened 10 until the interrupting device has operated.

3. An attachment for telephones, consisting of a rotary interrupting element connected in circuit with the telephone primary circuit, means for rotating said interrupting element, a movable member assembled with the telephone receiver hook for actuating said means, and locking means engaging said movable member when the telephone receiver hook rises for preventing said hook 20 from being lowered to open the circuit before the interrupting element has operated.

4. An attachment for telephones, comprising

ing a casing, a rotary interrupter within the casing connected in parallel with the telephone primary circuit, actuating mechanism operatively connected with said interrupter, a movable arm connected to the telephone receiver hook and operating to actuate said mechanism when the receiver hook is raised, a locking member within the casing, 25 cam means within the casing for actuating said locking member, and a keeper on said movable arm to engage said locking member when the receiver hook is raised to prevent the said hook from being lowered until the 30 interrupter has operated.

In testimony whereof, we affix our signatures in presence of two witnesses.

WILLARD C. FISK.
HARRY L. WHITE.
